UNITED STATES PATENT OFFICE.

JULIUS BRENZINGER, OF FAIRFIELD, CONNECTICUT, ASSIGNOR TO THE MAX AMS MACHINE COMPANY, OF BRIDGEPORT, CONNECTICUT, A CORPORATION OF NEW YORK.

SEAMING MECHANISM.

Application filed August 17, 1922. Serial No. 582,378.

To all whom it may concern:

Be it known that I, JULIUS BRENZINGER, a citizen of the United States, and a resident of Fairfield, in the county of Fairfield and State of Connecticut, have invented 5 certain new and useful Improvements in Seaming Mechanism, of which the following is a specification.

This invention relates to seaming mechanism for containers and covers and has 10 more particular reference to that part of the seaming mechanism which relates to the flattening or finishing operation. The main object and feature of the invention resides in 15 the production of a better and more reliable seam.

In the accompanying drawings, the invention is shown in a concrete and preferred form in which—

20 Fig. 1 is a vertical sectional view through a seaming mechanism showing the means for effecting the preliminary or curling operation.

25 Fig. 2 is an enlarged detail view showing the action of the parts of Fig. 1 on a container and cover.

30 Fig. 3 is a vertical sectional view through a seaming mechanism showing the means for effecting the finishing or flattening operation.

Fig. 4 is an enlarged detail view showing the action of the parts of Fig. 3 on a container and cover.

35 Referring to Figs. 1 and 2, 1 indicates a chuck and 2 is the seaming roller. These parts may be of standard construction and it will be understood that either container

30 or seaming roller 2 may rotate as may be desired and that the seaming roller has an in-and-out movement in the usual way to effect the preliminary or curling operation.

40 The chuck is provided with a head 4 that enters a depression 5 in cover 6; and the seaming roller is provided with a seaming surface 7 that, by pressure against the flanges of the container and cover, produces a preliminary curling of the seam to be formed.

45 As above indicated, this is standard construction and serves well enough for the preliminary or curling operation which is merely a loose interlocking of the flanges of the container and cover but, when it comes to

the flattening or finishing operation, different problems from those to be found in the 55 curling operation are encountered. As is well known, the usual practice in machines of this kind is to construct the means for effecting the flattening or finishing operation exactly the same as those just described in 60 connection with the preliminary or curling operation except for the shape of the seaming surface. This is not always productive of the best results and that for several reasons. When the finishing or flattening surface is brought home against the seam it sometimes happens that the seam is turned over inwardly instead of downwardly or that the metal flows in above the head 4 thereby producing inwardly projecting 65 burs. At other times the metal is pinched and the seam is partly destroyed. Again, it may happen that head 4 will press countersunk part of the cover deeper into the container thereby reducing the extent of interlocking between the container and cover and to prevent this latter condition recourse is had to a very fine adjustment between the lower pedestal and the head, which adjustment, unless made very carefully, will prevent proper clamping of the container and thereby, in machines of the type where the work rotates, prevent proper rotation of the work thereby keeping the flattening roller from rolling the seam tight all around the 70 can. In addition, since the seaming roller depends for its own axial rotation upon frictional contact with the work, such rotation must necessarily vary with different operating conditions.

75 Turning now our attention to Figs. 3 and 4, which show the flattening or finishing roller, it will be noted that chuck 8 is provided, in addition to head 9 fitting within the depression 10 of cover 11, with a circumferential flange 12, above said head 9, of greater diameter than that of the container to be seamed, the circumferential portion of the cover bearing against the underside 17 of said flange. It will be 80 further seen that seaming roller 13, in addition to flattening or finishing surface 14, is provided with a circumferential groove 15 into which flange 12 extends when the seaming tool approaches inwardly toward 85 the work, said groove affording an upper

surface 16 on the seaming tool engaging lower surface 17 of the flange. It will be understood that with this construction it is impossible for the seam to turn over inwardly by reason of flange 12; also that it is not necessary to effect any extremely delicate adjustment between the chuck and pedestal but that the container can be gripped tightly between said chuck and pedestal thereby insuring proper rotation of the parts and also preventing undue depression of the cover into the container. In addition, the downwardly facing part or surface 18 of groove 15 will be pressed against the upper part or surface 19 of flange 12 so that uniform rotation of the seaming roller around its axis is assured by the resulting frictional contact.

I claim:

20 1. Seaming mechanism comprising a chuck having a head to enter the depressed portion of a container cover and a circumferential flange, of greater diameter than the container to be seamed and in a plane

above the latter, against the underside of 25 which the circumferential portion of the cover bears, and a coacting seaming roller having a seaming surface and having an upper surface above the seaming surface engaging the lower surface of the flange. 30

2. Seaming mechanism comprising a chuck having a head to enter the depressed portion of a container cover and a circumferential flange, of greater diameter than the container to be seamed and in a plane 35 above the latter, against the underside of which the circumferential portion of the cover bears, and a coacting seaming roller having a seaming surface and having a circumferential groove above the seaming 40 surface to receive, and engage both the upper and lower surfaces of, the flange of the chuck.

Signed at New York, in the county of New York and State of New York, this 45 15th day of August, 1922.

JULIUS BRENZINGER.
